UNITED STATES PATENT OFFICE

JOHN A. WATCHER, OF JACKSON, MINNESOTA

SECTIONAL SMOKE FLUE

Application filed March 11, 1930. Serial No. 434,978.

This invention relates to certain improvements and refinements embodied in a sectional knock-down smoke flue or pipe such as is used in association with furnaces, boilers, hot water heaters, chimney extensions, and the like.

In carrying the invention into practice, I have developed a smoke pipe which is characterized by certain structural distinctions and features such as are mechanically associated and allied to form a practical and novel contribution to the prior art.

The particular features and advantages will become more readily apparent from the following description and drawings.

In the drawings:

Figure 1 is a sectional view of a fragmentary portion of a smoke pipe constructed in accordance with the present invention.

Figure 2 is a fragmentary side elevational view thereof.

Figure 3 is a horizontal section.

Figure 4 is a view similar to Figure 3 showing a corrugated dial of pipe length.

Referring now to the drawings by reference numerals, it will be seen in Figure 2 that I have shown a pair of pipe lengths 5 and 6 respectively which may be of suitable cross sectional shape and either corrugated as shown in Figure 4, or of flattened formation as seen in Figure 3. Each pipe length is composed of companionate half sections 7 and 8 whose longitudinal edges are disposed in overlapping and appropriately connected relationship to define a smoke-proof joint.

For example as seen in Figure 3, the joint may be of the single flange type as represented at 9 or may be of the form shown at 10 which includes a channel 11 on one section and an offset flange or lip 12 on the other section fitting into the channel.

The numeral 13 designates guides and retention projections which serve to hold in place a clamping ring or band 14 whose free ends are fastened together by a bolt as shown at 15 in Figure 2. This clamping band is for holding the half sections 7 and 8 in assembled relationship and it allows for expansion and contraction and adjustment.

The upper end of the female section or pipe length 5 is formed with an outwardly offset annulus defining a circular rim as at 16 which receives the adjacent end of the male length 6. The shoulder defined by the offset rim cooperates with the lugs 17 in holding the upper clamping band 18 in place. The lugs 17 cooperate with similar lugs 19 to accommodate the connecting and retaining bolts 20.

There are two kinds, one the split section flue and the other the solid section flue. Said flues can be made up in various lengths, varying from one foot to three feet, the diameter being from eight inches to 24 inches, the idea being that the flues can be joined together to make the length of stack desired. The pipes are corrugated in order to take care of expansion and contraction.

The lugs, with bolts running through vertically, are for the purpose of holding joints together tightly when lowering the flue in long pieces. The bands running around said flue are for the purpose of holding the same together firmly. Lugs to be used on ends of bands and for drawing the same together are so constructed as to take care of expansion and contraction of the flue, due to change of temperature. Joints are all to be filled with furnace cement when assembled for installation.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

I claim:

In a smoke-stack construction of the class described, a male pipe section comprising a pair of separable half sections having their longitudinal edges joined together in overlapping relationship, a pair of diametrically opposite apertured lugs carried by said male section, a female section composed of a pair of half sections also having their meeting

edges joined together in overlapping relationship, the upper end of the female section being formed with an offset annular rim telescopically receiving the adjacent companion 5 end of the first-named section, said female section being provided at a point below said rim with outstanding apertured lugs, a split clamping band surrounding said female section and resting on the second named lugs and 10 confined beneath the shoulder defined by said rim, and connecting bolts passing through the apertures in the co-related lugs of the respective sections.

In testimony whereof I affix my signature.
15 JOHN A. WATCHER.
